UNITED STATES PATENT OFFICE.

CALVIN B. PATCH, OF GLENELLYN, ILLINOIS, ASSIGNOR TO WILLIAM H. MINER, OF CHAZY, NEW YORK.

RAILWAY-CAR SIDE BEARING.

1,250,497.

Specification of Letters Patent. Patented Dec. 18, 1917.

Application filed July 14, 1916. Serial No. 109,234.

To all whom it may concern:

Be it known that I, CALVIN B. PATCH, a citizen of the United States, residing at Glenellyn, in the county of DuPage and 5 State of Illinois, have invented a certain new and useful Improvement in Railway-Car Side Bearings, of which the following is a full, clear, concise, and exact description, reference being had to the accompanying drawings, forming a part of this specification.

This invention relates to improvements in railway car side bearing.

One object of the invention is to provide 15 a simple, relatively cheap roller side bearing for railway cars and so arranged that the roller will be automatically returned to central or normal position after each actuation.

In the drawing forming a part of this 20 specification, Figure 1 is an end elevation of portions of a truck and body bolster of a car showing my improvements in connection therewith. Fig. 2 is an enlarged, longitudinal vertical section of the side bearing proper 25 taken on the line 2—2 of Fig. 1. Fig. 3 is a vertical transverse section taken substantially on the line 3—3 of Fig. 2. And Fig. 4 is a perspective view of one of the spring followers.

30 In said drawing, 10 denotes the body bolster and 11 the truck bolster which are pivotally connected at their centers in the usual manner. As shown, the body bolster is provided with a striking plate 12 and the truck bolster has applied thereto the improved side bearing designated generally by the reference A.

The improved side bearing A preferably 40 comprises a base member or casting B which is riveted or otherwise suitably secured to the truck bolster, and an anti-friction roller C. The base member B is of substantially box-like form, open at the top, and has outwardly extended bottom flanges 13 through 45 which pass the securing means, and on its interior, the base member is provided with a suitable inserted tread or wear plate 14 on which the roller C operates.

The roller retaining plate or base casting 50 B has parallel side walls 15—15 and curved end walls 16—16 which limit the movements of the roller C. The roller C, as shown, comprises two sections C¹ and C² connected by a central axle or journal 17 of reduced

diameter. Each of the end walls 16 of the 55 base casting is provided on its interior with a boss 18 within which is slidably mounted a non-circular bar 19 headed at its inner end as indicated at 20. Slidably mounted on each of said bars 19 at their inner ends, 60 is a spring follower 21 which fits between the sections C¹ and C² of the roller and engages the central axle portion 17, each follower 21 being curved on its inner face to fit the axle portion 17. Also mounted on each of 65 said bars 19 is a spring 22 which together coöperate to maintain the roller C in central or normal position.

Upon movement of the roller to either side of its normal position, one of the followers 70 21 and the bar 19 by which it is carried, will be forced outwardly against the action of the spring 22. Upon release of the pressure on the roller, the spring 22 will expand, thus forcing the roller back to central position 75 and returning the bar 19 and its corresponding spring follower to normal position.

I claim:

1. In a roller side bearing, the combination 80 with a base casting, of a roller mounted within said base casting, the roller comprising two sections spaced apart and united by a central portion of reduced diameter, oppositely arranged bars slidably mounted in the 85 end walls of the base casting, the inner ends of said bars extending into the space between the two sections of the roller and springs for retaining said bars in normal position.

2. In a roller side bearing, the combination 90 with a hollow base casting, a roller mounted within said casting, having a central portion of reduced diameter, bars on opposite sides of said roller slidably mounted with respect to said base casting, followers 95 on the ends of said bars engaging said reduced portion of the roller, and springs mounted on said bars extending between the end walls of the base casting and said followers.

In witness that I claim the foregoing I have hereunto subscribed my name this 12th day of July, 1916.

CALVIN B. PATCH.

Witnesses:

ELIZABETH M. BRITT,
GOLDIE A. BISHOP.
